UNITED STATES PATENT OFFICE.

ANTON C. SCHMELZER, OF SPRINGFIELD, MASSACHUSETTS, ASSIGNEE TO SCHMELZER & ARTHUR MFG. CO., OF SPRINGFIELD, MASSACHUSETTS.

FLUE-CLEANER.

1,160,658.

Specification of Letters Patent. Patented Nov. 16, 1915.

Application filed March 25, 1915. Serial No. 16,883.

To all whom it may concern:

Be it known that I, ANTON C. SCHMELZER, a subject of the Emperor of Austria-Hungary, and a resident of Springfield, in the county of Hampden and State of Massachusetts, have invented certain new and useful Improvements in Flue-Cleaners, of which the following is a specification.

My invention relates to means for cleaning the flues of steam boilers, and one of the main objects thereof is to provide a device whereby a plurality of jets of steam may be directed into said flues from a tubular arm adapted to be swung in front of the open ends of said flues.

A further object is to provide means for mounting the device directly to the bottom of the interior of the boiler.

A further object is to provide means exterior of the boiler for actuating a pinion which in turn actuates a gear carried by a member of the steam conduit.

A further object is to provide a housing for the actuating gears and which is split on the line of the gears, thereby facilitating the assembling thereof; and further objects are to provide such devices which are simple in construction and use; highly efficient in cleaning the flues of soot and thus increasing the efficiency of the boiler and securing full efficiency of the fuel, readily installed, and comparatively inexpensive.

My invention is fully described in the following specification, of which the accompanying drawings form a part, in which like reference characters are used to designate like parts in each of the views, and in which—

Figure 1 is a side elevation of a boiler, partly broken away to show my invention therein; Fig. 2 is an end elevation thereof, on the line 2—2 of Fig. 1; Fig. 3 is an enlarged, sectional, view of the invention detached from the boiler; and Fig. 4 is a section on the line 4—4 of Fig. 3.

In the drawings forming a part of this application I have shown a present preferred form of embodiment of my invention mounted in a boiler shell 4 having a plurality of conventional flues 5 therein, and a covering plate 6, the invention being mounted adjacent the open ends of the flues which it is desired to cleanse of soot or other deposits.

The invention consists of a tube 7 adapted

to be bolted to the floor of the boiler, and having a vertical rod 8 adjustable therein by means of set-screws 9; said rod is threaded into a casing 10 and locked therein by means of a set screw 11. The casing 10 is composed of two members, 10^a and 10^b, joined on a line 10^c, the former member having a steam passage 12 therein, one portion of which is vertical and connected with a steam inlet pipe 13, and the lower portion of which is horizontally arranged and registers with a bore 14 in a cylinder 15 rotatable in a bore 16 in the member 10^b; said cylinder 15 carries a gear 17 at its end adjacent the joint between the members 10^a and 10^b to allow the assembling of said cylinder and gear within the member 10^b. Enmeshed with the gear 17 is a pinion 18 carried at the end of a shaft 19 passed through and rotatable in the member 10^a, whereby said cylinder 15 may be rotated, and I provide means 20, of any desired kind, to rotate the shaft 19.

The cylinder 15 has a screw-threaded extension 15^a thereon and upon which is screwed a collar 22 locked thereto by means of a set-screw 22^a and serving, with the member 10^b, as confining means for a series of balls 22^b; to the outer end of the extension 15^a is connected a plate 23 which carries a T-connection 24 provided with a plate 24^a held in adjustable position upon the plate 23 by means of a bolt 23^a; the T-connection carries a tube 26 closed at top and bottom, as shown at 27 and 27^a, and said tube carries a counterweight 25, preferably adjustably mounted on a rod 25^a, and is provided with a plurality of spaced nipples 28 directed toward the ends of the flues 5 and so spaced as to register therewith when said tube is in normal, dependent, position; this tube is hereinafter referred to as a tubular arm, and it will be seen that, if the shaft 19 is rotated, said tubular arm is swung through an arc of a circle over the ends of all of the flues, and anti-frictionally because of the balls 22^b.

The steam inlet pipe 13 is connected with the steam chamber of the boiler at any desired point, not shown, and a control valve 29 is provided therefor; it will be seen that, if the valve 29 be opened, the steam passes through the cylinder 15, connected arm 26, and the nipples 28, and enters the boiler flues under high pressure because of the relatively small bores in the nipples; the de-

posits in the flues are blown through and out of the flues by this steam, and, if the arm 26 be swung while the live steam is thus passing through the nipples 28, said steam is admitted to all of the flues, and they are all cleaned.

The device requires but little room within the boiler, and may be readily installed, all that is necessary being to drill the holes for the bolts of the flanged tube 7, for the inlet pipe 13, and for the shaft 19, and the assembling may be accomplished without other change in the boiler; a few movements of the shaft actuating means at intervals will keep the flues absolutely free from soot, with the consequent increased efficiency of the boiler for the fuel consumption, and this may be accomplished without drawing the fires and cooling the boiler, and without interfering in any way with its normal functions. It will also be seen that but few parts are required for a thoroughly operative device, the geared cylinder 15 being the connecting link not only for the operation of the tubular arm 26, but also for the supply of steam thereto, thus simplifying the construction, minimizing the chances of any of the parts getting out of order to require repair, and very materially reducing the cost of the device, and the split casing 10 lends itself to this economical construction by enabling the quick assembling of the parts, and giving ready access thereto when desired.

With a reservation to myself of all such changes in and modifications of the details shown and described as come within the scope of the following claims, what I claim as new, and desire to secure by Letters Patent, is:—

1. The combination in a boiler of a rod, a casing on said rod formed of two members, a cylinder rotatable in one member, a collar on said cylinder, a gear on the opposite end of said cylinder, a pinion recessed in said member and engaged with said gear, said gear and pinion being arranged along the plane of contact of both members, means held in the other member for actuating said pinion, means on said last named member to lead steam to said cylinder, a tube carried at the end of said cylinder, and a plurality of nipples along said tube.

2. The combination in a boiler of a rod, a casing on said rod, a cylinder rotatable in said casing, means for rotating said cylinder, means for leading steam to said cylinder, a plate carried by said cylinder, a supplemental plate adjustably connected with said plate, and a perforated tube carried by said supplemental plate.

In testimony whereof I have signed my name to this specification in the presence of two subscribing witnesses.

ANTON C. SCHMELZER.
